[57] CLAIM

The ornamental design for a massaging chair, as shown and described.

DESCRIPTION

FIG. 1 is a front elevational view of the massaging chair of our design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view showing the massaging chair when the footrest is lowered;

FIG. 8 is a right side elevational view showing the massaging chair when the backrest is inclined rearward;

FIG. 9 is a right side elevational view showing the massaging chair when the footrest is extended;

FIG. 10 is a right side elevational view showing the massaging chair when the backrest is inclined rearward and the foot rest is extended;

FIG. 11 is a perspective view showing how an individual, shown in phantom, uses the massaging chair; and,

FIG. 12 is a right side elevational view illustrating how an individual, shown in phantom, uses the massaging chair.

The broken line showing of a human form in FIGS. 11 and 12 and the adjustment handle in FIGS. 5-10 are for environmental purposes only and form no part of the claimed design.
